LIGHT REFLECTING DEVICE

Stanley S. Cramer, Haddon Heights, N. J., assignor to Radio Condenser Company, Camden, N. J.

Application June 24, 1935, Serial No. 28,089

2 Claims. (Cl. 88—82)

This invention relates to the design of a reflecting unit to be used in connection with street signs which reflect the light directed against them from the lamps of approaching vehicles.

- 5 In my application Serial No. 626,489, filed July 30, 1932, now Patent 2,014,558, issued September 17, 1935, I have shown and described a particular construction of sign and certain types of light-reflecting units adapted for use therewith. 10 It is the principal object of my present invention to provide a reflecting unit for such signs which has certain advantages over the units shown in said patent.

In order to illustrate the application of my 15 new reflecting unit, I have chosen to show it in connection with the sign construction shown in my prior patent previously referred to, and in the drawing:

Figure 1 is a fragmentary portion of a sign in 20 which one letter of a word is shown, one of my improved units being illustrated in connection with the letter.

Figure 2 is a side view of Figure 1, a portion 25 being broken away to show the reflecting unit in elevation.

Figure 3 is a sectional view through my improved unit as attached to the mounting of Figure 1.

Figure 4 is a rear view of the unit per se minus 30 the retaining cap.

Figure 5 is a view of the bottom of the retaining cap looking at the outside.

Figure 6 is a fragmentary view of a modified 35 form of means for holding the reflecting unit casing to a support member.

In the various views of the drawing, 1 is a mounting plate which may be colored if desired. On the plate 1 is carried an auxiliary plate 2 which of itself may be fastened in any satisfactory way, as by spot-welding, to the mounting plate 1. However, as illustrated in the drawing, the auxiliary plate 2 is fastened to the mounting plate 1 by means of the reflecting units themselves. The auxiliary plate 2 may be a different 45 color from the mounting plate 1 and is provided with a plurality of holes 3 to receive a number of the reflecting units to make up the outline of a letter or number.

In my improved form of reflecting unit, the 50 holder or casing 4 has a shoulder 5 which supports a spherically curved reflector 6. Nested in the reflector 6 is a ball or spherical member 7 of glass, the same being held in its seat by spinning or forcing inwardly the outer edge 8 of the 55 holder or casing 4, it being understood that this

inwardly spun portion is located outwardly beyond the center of the ball 7. The bottom of the holder or casing 4 has fingers 9 and 10 punched outwardly therefrom and in opposite directions so that they are spaced a considerable distance 5 apart and on opposite sides of vertical and horizontal planes passing through the axis of the casing. The length of the fingers 9 and 10 of course will depend on the diameter of the bottom of the casing 4 and, as illustrated, the slots 11 10 formed by punching the fingers extend substantially across the entire bottom of the casing.

The casing 4 has a rim 12 to engage the auxiliary plate 2 and after it has been placed in position through the hole 3 in the auxiliary plate 2 15 and the corresponding hole in the support 1, a retaining cap 13, provided with slots or orifices 14 adapted to receive the fingers 9 and 10, is placed in position so that a flange 15 on the cap 13 engages a rear portion of the support plate 20 1. After the cap 13 has thus been put in position as shown in Figure 3, the ends of the fingers 9 and 10 are bent over the bottom of the cap 25 as indicated at 16, thereby securely anchoring the unit to the mounting plate 1 and holding 25 the auxiliary plate 2 in position as has been described.

By utilizing this construction, all of the work 30 may be done on a press, thereby eliminating the tapping of a hole in the casing for use of a screw, etc., as in my prior construction. In addition, not only is the cost of construction reduced, but the cost of assembly is materially reduced as it will be seen a considerable number of the units 35 may be utilized in a given sign. While Figure 3 shows an outwardly turned flange 15 around the rim of the cap 13, this flange may be irregular just as it comes from the drawing press, as an 40 irregular edge will give a better grip on the main mounting plate 1, particularly if this mounting plate is other than metal.

In Figure 6 I have shown a mounting plate 45 which may be of wood or some other material than metal, and hence thicker. In other words, the mounting plate may be of any suitable thickness, and when such a mounting plate is used, I prefer to use a small binding plate 18 of suitable metal which is perforated to receive the bent-over ends 16 of the fingers 9 and 10, it being understood that the dimension of the plate 18 is 50 sufficient to cover the hole for the casing 4.

What I claim is:

1. A structural device for building up indicia for street signs which includes an integral, assembled unit ready to be passed through a hole 55

in a mounting, said unit consisting of a cup-shaped casing having a rim for engaging the front of the mounting and carrying a light-transmitting member therewithin and a reflector near the rim and within which the light-transmitting member is nested; the bottom of the said casing having a pair of lugs punched outwardly therefrom in spaced relation, and a clamping member having slots therein to receive said lugs which are then adapted to be bent over said clamping member to force it into engagement with the rear of the mounting to hold the said casing in the mounting.

2. A structural device for building up indicia for street signs which includes an integral, as-

sembled unit ready to be passed through a hole in a mounting, said unit consisting of a cup-shaped casing having a rim for engaging the front of the mounting and carrying a glass ball deeply within the casing, and a reflector near the rim and within which the ball is nested; the bottom of the said casing having a pair of lugs punched outwardly therefrom in spaced relation and a cup-shaped retaining cap fitting over said casing and engaging the rear of the mounting, said casing having slots in the bottom thereof to receive said lugs which are adapted to be bent over the bottom of the cap after the casing and cap have been put in position on the mounting.
